UNITED STATES PATENT OFFICE.

OTTO NITSCH, OF HARBURG-ON-THE-ELBE, GERMANY.

ELECTRIC LOCK AND ALARM APPARATUS.

1,160,681.

Specification of Letters Patent. Patented June 16, 1914.

Application filed January 29, 1914. Serial No. 815,577.

To all whom it may concern:

Be it known that I, OTTO NITSCH, a subject of the King of Prussia, and resident of 2 Wilsdorferstrasse, Harburg-on-the-Elbe, 5 in the Empire of Germany, have invented a new and useful Improved Electrical Lock and Alarm Apparatus, of which the following is a specification.

The present invention relates to an improved electric safety device for door locks 10 in combination with a signal or alarm apparatus.

Special objects of the invention are to render more efficient, serviceable and durable in operation safety devices of the kind referred to.

With these ends in view the invention consists in the novel combination, arrangement and adaptation of parts, all as more 20 fully hereinafter explained, shown in the accompanying drawings and finally set out in the appended claim.

In the annexed drawing is shown diagrammatically one mode of carrying into 25 practice my invention.

My invention being suitable for door locks of any desired type which employs a slide- 30 able bolt for locking the door, I have deemed it unnecessary to illustrate the door lock, but have restricted the illustration to the slideable bolt, which is essential in the combination constituting my invention.

The slideable bolt *a*, besides the ordinary arresting mechanism provided in the lock 35 case, is under the influence of an accessory locking arrangement formed by the armature *b* of an electromagnet *c*¹. This accessory locking arrangement is rendered effective by means of a nose *c* on the armature *b* entering a notch *d* or *e* of the slideable bolt *a*, the notches *d* and *e* being provided in 40 such co-relative positions that the slideable bolt *a* assumes its locking position when the nose *c* enters the notch *d* and that it assumes 45 its inoperative position when the nose *c* enters the notch *e*.

The armature *b* is pivotally attached to the lock case by means of the pin *f* in such a position, that it separates from the notch 50 *d* or *e* respectively on being energized, thus liberating the bolt *a* which can then be moved either in one or the other direction.

The electromagnet *c*¹ is in conductive connection with the source of electricity *g* by 55 means of suitably arranged and protected line wires, the electric circuit containing

also the cut out *h* and the push-button switch *i*. A second push-button switch *k* is arranged in the proximity of the door lock at the outside of the door, in order to enable 60 the door lock to be opened from outside. This second push-button switch *k* is fitted for two contacts *l* and *m*, so that on its actuation the alarm bell *n* rings previous to the liberation of the slideable bolt *a* from the 65 lever armature *b*. The contact *l* closes an electric circuit over the line wire *o*, the bell *n*, the line wire *p*, the source of electricity *g* and the line wire *q* and thus actuates the 70 alarm bell *n*. When the push-button *k* reaches the contact *m* an electric circuit is closed, which contains the electromagnet *c*¹, this electric circuit being constituted by the 75 source of electricity *g*, the line wire *q*, the push-button *k*, the electromagnet *c*¹, the line wire *s* and the cut out *h*. On thus energizing the electromagnet *c*¹ the armature *b* is attracted and in consequence thereof the 80 slideable bolt *a* is disengaged from the nose *c*, so that the door lock can be opened.

When it is required to open the locked door from inside, the push-button *i* in the proximity of the source of electricity *g* has to be actuated. The electromagnet *c*¹ is in this case energized by the current flowing 85 through the circuit constituted by the source of electricity *g*, push-button *i*, line wire *r*, electromagnet *c*¹, line wire *s* and cut out *h*. The electromagnet *c*¹ thus attracting the 90 armature *b*, the door can be opened and locked again. The alarm bell *n* is also sounded when opening the locked door from inside but by only one electric circuit, which is caused by the armature *b* touching the contact *t*. This electric circuit is closed 95 over the source of electricity *g*, the push-button *i*, the line wire *r*, the electromagnet *c*¹, the contact *t*, the line wire *o*, the alarm bell *n* and the line wire *p*.

If an unauthorized person attempts to 100 open the locked door from outside and, to prevent the alarm apparatus from being sounded, tries to evade the push-button *k* by conductively connecting the contacts *u* and *m*, say by means of a piece of wire, the alarm bell *n* still sounds by virtue of the 105 electric circuit closed over the source of electricity *g*, line wire *q*, wire connecting *u* and *m* at the push-button *k*, armature contact *t*, line wire *o*, alarm bell *n* and line wire *p*. 110 This actuation of the alarm apparatus is independent from the cut out *h*.

The improved locking and alarm arrangement affords a reliable insurance against the opening of locked doors by unauthorized persons.

5 What I do claim as my invention, and desire to secure by Letters Patent, is:

The combination with the bolt of a door lock, of an electromagnet, a pivoted armature lever, a nose thereon adapted to engage
10 in a notch in the bolt both when thrown and when retracted, a spring contact touching the armature lever when same is attracted, line wires separately leading from the electromagnet, the armature lever and the
15 spring contact to a common source of electricity, an alarm bell, a cut out and a push-button preferably arranged in close proximity to the source of electricity inside the door and in conductive connection with the

electromagnet, the armature lever and the 20 spring contact, a push-button outside the door near the door lock, two contacts for this push-button arranged in conductive connection with the source of electricity and the electromagnet for releasing the door lock, so 25 that the alarm bell sounds even if the ordinary alarm circuit is intentionally disturbed previous to actuating the push-button for electrically releasing the bolt of the door lock, substantially as described and shown 30 and for the purposes set forth.

In witness whereof I have hereunto signed my name this 17th day of January 1914, in the presence of two subscribing witnesses.

OTTO NITSCH.
